DRAFT GEAR

Application filed November 13, 1928. Serial No. 319,064.

Our invention relates to improvements in draft gears and is directed to providing a draft gear with a much greater spring capacity than has hitherto been used and in providing means for frictionally retarding the recoil action of the springs.

In modern friction draft gears the frictional resistance provides a far greater proportion of the shock absorbing or cushioning power of the gear than does the spring capacity. As a result the gear action is not as smooth as is desired, for the reason that the frictional resistance developed by rubbing metal on metal under heavy pressures, which is greatly in excess of the spring resistance, is apt to cause a series of perceptible jolts and jars which it is desirable to eliminate. For the purpose of overcoming the rough riding action of such gears we have provided a draft gear with sufficiently high spring capacity to take care of all steady running loads, to which we have added frictional capacity, which, together with the spring capacity, is adequate to resist impact shocks. Our improved gear on release also develops sufficient friction to retard or snub the recoil of the high capacity springs to a point which will assure smooth riding. Our invention also comprises various features which we shall hereinafter describe and claim.

In the accompanying drawings, Fig. 1 is a top plan view, partly in section, of a draft gear embodying our invention; Fig. 2 is a side elevation partly in section; Fig. 3 is a section on lines III—III of Fig. 1; Fig. 4 is an elevation of the inner surface of the wedge; and Figs. 5 and 6 are diagrammatic views of modified forms of our invention.

Referring more particularly to the drawings, the gear has a case 2, preferably rectangular in form, in opposite sides 3 of which are seated the friction members 4, each of which is preferably a rectangular block having at its inner end a lateral projection 5. In each side wall 3 is a recess 6 for the projection 5, which preferably has sufficient clearance to permit a limited movement of the frictional member 4 longitudinally as well as laterally of the case. To resist the inward thrust of the frictional members 4, the case

2 at the rear of the recesses 6 has abutments 6' against which the members 4 bear at their rear ends, and these abutments 6' are braced by the diverging ribs 7, which extend back to and are merged into the rear end 8 of the 55 case.

On the opposite sides of each of the friction members 4 and in frictional engagement therewith are arranged friction shoes 9, two friction members 4 and four shoes 9 being 60 shown in the embodiment of my invention here illustrated. The inclined forward faces 10 of the shoes 9 are engaged by correspondingly inclined faces 11 of the wedge 12. Each shoe face 10 has also an inclined recess 65 13 into which fits a correspondingly inclined rib or flange 14 onto the wedge 12 for the purpose of maintaining the shoes and wedging faces in alignment and of preventing the shoes 9 from working laterally over to and 70 abrading the sides of the case 2.

The wedge 12 has a central projection 15 which forms a bearing for the forward end of the central spring 16 and also serves to hold the friction members from working inwardly from the seat against the inner surface of the case 2. The forward ends of the side springs 17, of which we have shown two for each pair of shoes, bear against the spring follower 18, and each spring follower 80 bears against the vertically disposed rear faces 19 of the projections 20 on a pair of the shoes 9. The backs of the shoes are also recessed at 21, and the friction members at 22, to provide clearance, respectively, for 85 the side springs 17 and the central spring 16.

The wedge 12 is heavily braced across its central portion by the ribs 23, which tie together the opposing wedge faces to resist the heavy bursting stresses to which the 90 wedge is subjected.

When under strong compression, the wedge 12 drives the shoes 9 rearwardly against the pressure of the springs 17 and the wedge itself directly against the pressure of the spring 95 16. At the same time a certain amount of friction is developed between the sides of the friction members 4 and the faces of the friction shoes 9 in contact with such sides, the amount of such friction being dependent 100

on the angle of inclination of the sides of the friction members to the longitudinal axis of the gear. The parts of the gear are proportioned so that just before the springs go solid the wedge will come into engagement with the end of the case and thereby protect the springs against oversolid blows.

As has been stated above, the projections 5 have a limited amount of clearance in their seats 6 in the case. This is for the purpose of permitting the members 4 to tip with the wedge 12 and shoes 9 in case an angular blow strikes the wedge 12, without disturbing the frictional grip of the parts. This lateral clearance also allows the members 4 to shift bodily laterally to compensate for inequalities in the size of the shoes. In release the frictional engagement of the shoes against the frictional members retards or dampens the recoil of the springs and thus prevents sudden shock or jar to the car during the restoration of the parts to their original positions.

In a gear of the type just described, in which the springs have a resistance under initial compression of about 21,000 pounds and a maximum resistance of about 76,000 pounds, i. e., approximately equal to the maximum sustained drawbar pull of a modern locomotive, we have found that the frictional resistance developed during compression was upwards of 75,000 pounds and was ample to take care of impact blows and the compression involved in sudden stops and starts. In release the frictional engagement between the shoes and friction members damped down or absorbed the spring recoil to such an extent that the whole release operation was effected without any sudden jar or shock.

In the structure of Figs. 1 to 4, inclusive, we have shown the engaging surfaces of the shoes and friction member substantially parallel to the line of draft or longitudinal center line of the gear. Where, however, it is desired to increase the frictional capacity the frictional faces of the gear may be tapered slightly from the front ends of the frictional members 34 toward their rear ends—that is, the frictional members are made to widen toward their rear ends. As is shown in Fig. 5, the dotted line *a* is parallel to the longitudinal center line of the gear and at an angle to the tapered face *b* of the friction member. With the frictional members 34 tapered approximately four-tenths of an inch in a foot, and a corresponding taper on the face of the shoes 39, we have found that the added frictional resistance of the gear will be upwards of 350,000 pounds, but on release the dampening or absorbing effect of the frictional elements upon the spring recoil will be lessened.

If it is desired to increase the dampening or absorbing effect of the frictional elements, this may be effected, as is shown in Fig. 6,

by reversing the taper on the shoes 49 and frictional members 44; that is, the front ends of the friction member are wider than their rear ends. A taper of the order of four-tenths of an inch in a foot, with a corresponding taper on the shoes, is sufficient to augment considerably the dampening or absorbing action of the frictional elements, but for purposes of illustration a somewhat greater taper is shown, the dotted lines *c* being parallel to the longitudinal center line of the gear and at an angle to the tapered faces *d* of the friction member. In such a construction the added frictional capacity of the gear under compression is materially decreased.

One of the advantages of our invention is that in any of its forms here illustrated a preliminary spring action of any desired extent can readily be obtained by providing sufficient clearance longitudinally between the lateral projections 5 of the friction members 4 and the recesses 6. A further advantage consists in the location of the friction members 4 in the sides of the case 2 and between the springs 17 together with the use of opposed, relatively short friction shoes arranged in pairs, which allows the maximum amount of space to be reserved for springs without encroaching upon the standard dimensions allowed for draft gears.

It will thus be seen that gears embodying our invention are capable of being used to meet a wide range of service conditions from very heavy freight to light passenger traffic.

The terms and expressions which we have employed are used as terms of description and not of limitation, and we have no intention, in the use of such terms and expressions, of excluding any mechanical equivalents of the features shown and described, or portions thereof, but recognize that various structural modifications are possible within the scope of the invention claimed.

What we claim is:

1. In a draft gear, a case, friction members anchored within the case, a pair of friction shoes in frictional engagement with each member, spring elements, a spring follower in engagement with each pair of shoes, a pair of said spring elements in engagement with each follower, and a wedge engaging all of the shoes, one of the spring elements engaging the wedge.

2. In a draft gear, a case, a plurality of friction members anchored in the sides of the case, a plurality of pairs of friction shoes, each pair in frictional engagement with a corresponding one of said members on opposite sides thereof, spring elements compressed by each pair of shoes, and a wedge engaging said shoes, the wedge and each shoe having a slot and projection engagement to guide the movement of the shoes.

3. In a draft gear, a case, friction members within the case, a pair of friction shoes in frictional engagement with each member, the shoes of each pair being in engagement with opposed sides of the corresponding friction member, spring elements compressed by said shoes and a wedge engaged by said shoes, the members being positioned in the casing adjacent the frictional zone thereof and so constructed and arranged in said casing as to move with said shoes in a direction at an angle to the axis of the casing to compensate for offcentered blows without disturbing the frictional grip of the shoes on the members.

4. In a draft gear, a case, at least one friction member extending longitudinally in the case, friction shoes in engagement with each such member and a wedge engaging the shoes, each such member being held substantially from longitudinal movement relative to the case but loosely secured thereto for bodily movement in a lateral direction relative to said case to compensate for offcentered blows without disturbing the frictional grip of the shoes on the member.

5. In a friction draft gear, a housing, a plurality of friction members mounted in said housing, friction shoes arranged on opposite sides of said friction members a wedge pressing said shoes against said members, and spring means resisting the movement of said shoes, said means being arranged on opposite sides of said friction members, and additional spring means between said members and resisting movement of said wedge.

6. In a friction draft gear, a rectangular housing, friction members mounted on opposite sides of said housing, a plurality of pairs of friction shoes, each of said pairs engaging opposite sides of said members, a wedge pressing said shoes against said friction members, a plurality of springs, one for each shoe and resisting the movement thereof, and a centrally located spring between said friction members and resisting movement of said wedge.

7. In a draft gear, a case, friction members anchored within the case and movable relatively to each other, a pair of friction shoes in frictional engagement with each member on opposed sides thereof, all of said shoes being so located in said case as to be cut by a common transverse plane, spring elements compressed by each pair of shoes, and a wedge engaging all of said shoes.

8. In a friction draft gear, a casing, a plurality of friction members anchored in the side walls thereof and extending inwardly of said casing, friction shoes in engagement with opposite sides of each of said friction members, a wedge engaging said shoes, and spring resistance means opposing movement of said wedge and arranged to prevent

disengagement of said friction members from said side walls.

9. In a draft gear, a case, friction members within the case, a pair of friction shoes in frictional engagement with each member on opposite sides thereof, spring elements compressed by said shoes, and a wedge engaged by said shoes, the members being loosely secured to the casing adjacent the frictional zone thereof for free angular movement relative to said case to compensate for off-centered blows without disturbing the frictional grip of the shoes on the members.

10. In a draft gear, a case, a friction member extending longitudinally in the case, friction shoes in engagement with said member on opposite sides thereof and a wedge engaging the shoes, said member being held substantially from longitudinal movement relative to the case but loosely secured thereto for bodily movement in a lateral direction relative to said case to compensate for off-centered blows without disturbing the frictional grip of the shoes on the member, and spring means opposing longitudinal movement of said shoes with respect to said case.

11. In a draft gear a case, friction members anchored within the case, a plurality of pairs of friction shoes each pair in frictional engagement with a corresponding one of said members, a plurality of spring followers each engaging a shoe cooperating with one friction member and a shoe cooperating with the other friction member, a pair of spring elements in engagement with each follower and a wedge engaging all of the shoes.

12. In a draft gear, a case, friction members anchored in the sides of the case, a plurality of pairs of friction shoes, each pair in frictional engagement with oppositely facing sides of a corresponding one of said members, a plurality of spring followers one engaging a plurality of said shoes and the other engaging others of said shoes, a pair of spring elements in engagement with each follower and a wedge engaging all of the shoes.

13. In a draft gear, a case, springs in said case and extending longitudinally thereof, friction members in separate zones of said case, each friction member being mounted in a space between different springs, friction shoes engaging the respective friction members, and wedging means cooperating with said shoes and resisted by said springs in compression of the gear, and an additional spring between said friction members and opposing movement of said wedging means.

14. In a draft gear, a case rectangular in cross section, springs in the respective corners of said case, a plurality of friction shoes one for each of said springs, a pair of friction members mounted in opposite walls of said case, opposite faces of one friction mem-

ber being engaged by a pair of said shoes and opposite faces of the other friction member being engaged by another pair of said shoes, and a wedge cooperating with said 5 shoes to move the latter in frictional engagement with said friction members and against the action of said springs, and another spring positioned centrally with respect to the first mentioned springs and between said 10 friction members for opposing movement of said wedge.

15. In a friction draft gear a spring housing, separate friction members anchored to opposite walls of said housing and extending inwardly thereof, friction shoes on opposite sides of said friction members, a wedge for forcing said shoes inwardly into frictional engagement with opposite sides of each of said friction members, each of said shoes 20 having a spring in alinement therewith for opposing movement thereof and a spring extending between said friction elements and opposing movement of said wedge.

In testimony whereof, we have signed our 25 names to this specification this 10th day of November, 1928.
